Primary Examiner — Vy N Koenig*Assistant Examiner* — Kimberly Barnes(74) *Attorney, Agent, or Firm* — Leason Ellis LLP(57) **CLAIM**

The ornamental design for a ramp with paneling, as shown and described.

DESCRIPTION

FIG. 1 is a front perspective view of a ramp with paneling according to our new design;

FIG. 2 is a rear perspective view of FIG. 1;

FIG. 3 is a right side view of the design of FIG. 1;

FIG. 4 is a left side view of the design of FIG. 1;

FIG. 5 is a top view of the design of FIG. 1;

FIG. 6 is a bottom view of the design of FIG. 1;

FIG. 7 is a front view of the design of FIG. 1; and,

FIG. 8 is a rear view of the design of FIG. 1.

The oblique lines on the upper panels of the ramp depict a transparent surface.

The broken lines shown in FIGS. 5 and 7 depict features of the ramp with paneling that form no part of the claimed design.

1 Claim, 5 Drawing Sheets(56)
